US00D930447S

(12) **United States Design Patent** (10) **Patent No.:** **US D930,447 S**
(45) **Date of Patent:** **** Sep. 14, 2021**

(54) **TIE-OUT STAKE**

(71) Applicant: **COMMERCE C.LABS INC.,**
Saint-donat (CA)

(72) Inventor: **Christophe Labarre**, Saint-donat (CA)

(73) Assignee: **COMMERCE C.LABS INC.,**
Saint-donat (CA)

(**) Term: **15 Years**

(21) Appl. No.: **29/723,920**

(22) Filed: **Feb. 12, 2020**

(51) LOC (13) Cl. **08-01**

(52) U.S. Cl.

USPC **D8/1; D30/154**

(58) **Field of Classification Search**

USPC D8/1, 391, 356, 388; D3/10; D30/154
